PERFORATION CLEANER AND BAILER

William J. Flury, Long Beach, Calif.

Application July 17, 1934, Serial No. 735,605

21 Claims. (Cl. 166—19)

This invention relates to a tool to be used in deep wells for cleaning out perforations of screens. In producing wells the perforations of these screens through which the oil flows frequently become clogged with dirt or asphalt and from time to time they must be cleared of these obstructions.

The tool is of a type which employs a low pressure air tight chamber. Bailers employing such an air tight low pressure or vacuum chamber have been used heretofore, which embodied a shoe at the lower end, and when this shoe struck the bottom of the well its upward movement operated to open a valve closing the lower end of the air tight chamber, thereby enabling the pressure in the well to cause an inrush of material into the bailer. In order to operate such a bailer, however, it is necessary for the shoe to encounter an obstruction in the well or the well bottom.

One of the objects of this invention is to produce a tool involving the use of an air tight chamber and constructed in such a way that the valve closing the air tight chamber can be opened within the well casing at a screen regardless of whether the well is obstructed at that point. In this way it is possible to develop a differential pressure between the interior of the well casing and the exterior at any point in the well whether it is obstructed or not, and the tool is not dependent upon a relative upward movement of the shoe or any part corresponding to the shoe.

A further object of the invention is to provide a tool of this general type involving the use of a low pressure air tight chamber and to provide a construction which will enable the chamber to be opened through the medium of a jar imparted to the upper end of the tool, which is preferably suspended on a sand line.

A further object of the invention is to provide a tool of this general type which can be readily operated through the medium of a jar imparted to the tool, to develop a differential pressure within a well casing at a screen, thereby developing an inrush of material or fluid through the perforations to clear the same; also to provide a tool of this type and operating in this way which is capable of having its parts assembled in a slightly altered relation so as to enable the tool to be used as a bailer on a well bottom.

A further object of the invention is to provide an improved method for cleaning out the perforations of well screens and for removing the material which is drawn into the well through the perforations by the operation of the tool,

In its general construction, the tool involves the use of a valve for maintaining the air tight low pressure chamber closed while the tool is running down the well. One of the objects of the invention is to provide a construction whereby the pressure in the well will assist in maintaining the valve closed; also to provide a construction for the tool involving the use of a relatively movable part which is held against movement while the tool is running down the well but which is mounted in such a way that it can be released by a jar, thereby permitting the same to have relative longitudinal movement on the body or relatively fixed part of the tool; and one of the objects of the invention is to provide improved means for utilizing this relative movement to effect the opening of the valve.

In the operation of bailers of this general type used heretofore, the entire weight of the tool rests on the well bottom when the valve opens and, while this results in charging the bailer through its shoe at the bottom of the bailer, there is a disadvantage that on account of the fact that the weight of the tool is resting on the well bottom, the tool tends to bury itself in the well bottom and may become "frozen", thereby causing delay and difficulty in freeing the tool to enable the bailing operation to be continued. One of the objects of the invention is to produce a tool of this general type involving the use of a low pressure air tight chamber, but in which the valve can be tripped and opened immediately that the bailer shoe strikes the well bottom or an obstruction in the well but without the entire weight of the tool resting on the shoe. In this way an efficient charging of the bailer occurs without any tendency for the bailer shoe to bury itself in the well bottom.

Further objects of the invention will appear hereinafter.

As regards the apparatus, this invention consists in the novel parts and the combination of parts to be described hereinafter, all of which contribute to produce an efficient perforation cleaner and bailer.

In the drawings:

Fig. 1 is a vertical section through a portion of a well casing and illustrating this tool in side elevation with the lower end of the tool located opposite the perforations as though in readiness to perform the perforation cleaning or clearing operation. In this view certain parts are broken away.

Fig. 2 is a partial side elevation and section

illustrating details of parts of this tool upon an enlarged scale, certain parts being broken away, and showing the valve in its open position.

Fig. 3 is a view similar to Figure 2 but showing the relation of the parts when the valve is in its closed position.

Fig. 4 is a section corresponding to Figure 2 but showing the actuator sleeve in side elevation and indicating the manner in which it operates to effect the opening of the valve. In this view the valve is indicated in its open position corresponding to Figure 2.

Fig. 5 is a horizontal section taken on the line 5—5 of Figure 4 and further illustrating details of the construction. Figure 5, however, is on a slightly larger scale than Figure 4.

Fig. 6 is a side elevation of a cam member which cooperates with the valve and actuator sleeve to effect the opening of the valve.

Fig. 7 is a view similar to Figures 2 and 4 and showing an arrangement of the parts of the tool to illustrate how the jar operated tool can be readily transformed into a tool the valve of which will be opened by a movement of a shoe at the bottom of the tool; and without all the weight resting on the shoe.

Fig. 8 is a horizontal cross section taken on the line 8—8 of Figure 7, and further illustrating details of this construction; and

Fig. 9 is a view similar to Figure 7, but illustrating an embodiment of the invention in which the tool can operate as a bailer on the well bottom without the entire weight of the tool resting upon the well bottom when the valve is tripped or opened to charge the bailer. In this construction, provision is made for guiding and packing the shoe close to its lower end, and so as to permit a very considerable free movement of the bailer shoe when it opens the valve.

Before proceeding to a more detailed description of the invention, it should be stated that the apparatus involves the use of a relatively fixed part, which is preferably suspended on a sand line, and on this relatively fixed part I mount a relatively movable part which is normally held against movement on the relatively fixed part by yieldable means capable of being dislodged by a jar imparted to the relatively fixed part. In using the tool for cleaning out perforations in the well screen, a jar imparted to the relatively fixed part releases the relatively movable part, and the relative movement of this part operates to effect the opening of the valve. The air-tight chamber within the tool may be at atmospheric pressure or, if desired, may be under partial vacuum. In any event the pressure within the air tight chamber is a low pressure with respect to the pressure existing within the well, either hydraulic or gas pressure. By reason of the presence of the low pressure air chamber, it follows that immediately that the valve is opened a sudden reduction in pressure on the interior of the casing at the screen is developed, and this causes a differential pressure between the interior of the casing at this point and the exterior. For this reason a sudden inrush of material from the well will occur through the perforations, thereby clearing them. The tool is preferably provided with a suction head so that the material that is dislodged from the perforations will be drawn into the sand chamber of the tool where it will be retained. The tool can then be run up to the mouth of the well and dumped.

When the tool is jarred to effect the opening of the valve in a perforation cleaning operation, the relatively movable member moves relatively downwardly on the relatively fixed part or body of the tool. Through the agency of an actuator sleeve carried by the relatively movable member and preferably involving the use of a substantially helical slot, the valve is opened. In accomplishing the opening of the valve, this actuator sleeve cooperates with a cam and the valve to effect a relative rotation of the valve and the cam. The actuator sleeve also preferably includes a longitudinal slot which cooperates with a projection on the cam member to prevent rotation of the actuator sleeve and thereby enabling the helical slot formed on it to cooperate with a projection or pin on the valve to effect relative rotary movement of the valve and cam. I have discovered that by constructing these parts so as to enable the projection on the cam member to run in the helical slot and by constructing the pin on the valve so that it can run in the longitudinal slot of the actuator sleeve, I can readily transform this tool into an efficient bottom bailer, in which the valve will be opened through the medium of the shoe striking the well bottom. And in connection with this bottom bailer, I also provide a construction which may be used, if desired, which will enable the tool to operate without the entire weight of the tool resting on the well bottom. This involves mounting the bailer shoe on a barrel that is relatively movable upwardly on the bailer mandrel, and in the operation of this tool the only weight on the well bottom is that of the barrel. However, as soon as this shoe strikes the well bottom, the valve immediately commences to open.

Referring more particularly to the parts and especially to Figures 1 and 2, I indicates a well casing having a screen 2 at a low level in the well and having perforations 3 through which the liquid, such as oil, flows into the casing 1. The tool is preferably provided at its upper end with an eye 4 to be attached to a sand line for running the tool down a well. The relatively fixed part of the tool embodies an upper barrel 5 carrying a mandrel 6 below the same, which may be considered the relatively fixed part of the tool. The lower portion of the mandrel 6 is enveloped in a lower barrel 7, see Figure 2, the lower end of which is threaded onto a coupling 8 and the upper end of this coupling is preferably formed into an actuator sleeve 9. The upper barrel 5 and the mandrel 6 are preferably provided with an air tight low pressure chamber 10 which is closed at the lower end of the mandrel by a valve 11 that seats, by an upward movement, on a suitable valve seat 12. The valve and seat are so constructed that the valve will be substantially air tight and so that it will maintain the low pressure in the air chamber while the tool is running down the well.

In the lower end of the mandrel I provide a cam member or cam sleeve 13, see Figure 6, which may be attached by threads to the lower end of the mandrel. This cam member or cam means 13 is preferably provided with two diametrically opposite cam edges 14 to cooperate with projections or pins, such as the pin 15, that project radially outwardly from the valve head. The side walls of this cam member 13 are cut away by forming windows 16 in the same, as illustrated in Figure 6. The valve is preferably provided with a stem 17 that is guid-

ed through the lower end of the cam member 13 and the cam member houses a coil spring 18 disposed around the valve stem that thrusts upwardly against the valve head and normally holds it on its seat. This spring, however, may be considered as a return spring for reseating the valve after it has been opened. The valve can be held closed, of course, by the relatively high pressure in the well but the use of such a spring is advisable where the pressure in the air chamber 10 is not lower than atmospheric pressure.

It should be understood that the lower barrel 7 is normally held in a relatively elevated position on the mandrel by yieldable means which 15 can be released by a jar. This yieldable means will be described hereinafter. When the jar occurs, the barrel 7 slides down on the mandrel and when it does so it is prevented from rotation by suitable means, preferably consisting of projections or pins 19, see Figures 2 and 6, which project outwardly from the cam member 13 at diametrically opposite points and which run in two longitudinal slots 20 formed in the actuator sleeve. The valve pins 15 project outwardly beyond the cam edges 14 and are received in substantially helical slots, such as the slot 21, formed in the actuator sleeve. Figure 3 shows these parts in their relation when the valve is closed. At this time the valve pins 15 will be located near the lower ends of the helical slots 21. When the barrel 7 slides downwardly, it will be evident that the slots 21 will cause a rotation of the valve on its longitudinal axis in a clockwise direction, or in a left hand direction as viewed in Figure 4. This will cause the pins 15 to ride up on the cam edges 14 and open the valve.

The tool is preferably constructed with a perforated suction head 22 which is attached to the lower end of a sand barrel 23, the upper end 40 of which is secured to the coupling 8, and above this suction head a bottom valve 24 (indicated in dotted lines in Figure 1) is provided which permits any material drawn into the perforations to pass up into the sand chamber and this material will be retained in the sand chamber by this flap valve.

Referring now to the means for yieldably supporting the lower barrel 7 on the mandrel, it should be said that this means involves the use 50 of a recess in the mandrel and a registering recess in the barrel. These recesses when they register together form a pocket to receive yieldable means, preferably in the form of a spring, and one of these parts, either the mandrel or the barrel, is preferably provided with an inclined shoulder which facilitates the release of the lower barrel when a jar is imparted to the mandrel. The preferred construction for this purpose is 55 illustrated in Figure 3 and involves providing the upper end of the barrel with a split sleeve or bushing 25 which is screwed down into the upper end of the body of the barrel. The inner face of this bushing 25 has a circumferential groove 26 cut in it which registers with a corresponding circumferential groove 27 cut in the mandrel. When these two grooves register together they form a pocket to receive a split spring ring 28 which tends, by its resiliency, to expand and in this expanded position it lies across the 60 meeting faces of the mandrel and the barrel so as to lock these parts yieldably together. The upper end of the groove 26 in the barrel is preferably formed with an inclined face 29, see Figure 2, and the upper edge of the spring ring 28 is correspondingly inclined. With this con-

struction it will be evident that if a sufficient jar or up snap is given to the mandrel, the inclined shoulder 29 will operate to compress the ring 28 into the groove 27, thereby releasing the barrel 7.

Figure 2 shows the position of the barrel after 5 release, the barrel having had sufficient movement to open the valve as indicated at the lower end of Figure 2. This downward movement of the barrel is limited by the bushing 25 striking the upper end of an integral head or large collar 10 30 formed on the mandrel. In order to insure that the downward movement of the barrel 7 will be free, it is preferable to provide air vents 31 through the wall of the barrel to prevent compressing any air above the head 30 within the 15 barrel.

The upper end of the head 30 is preferably of somewhat smaller diameter than the lower portion 32, which is of sufficient diameter to slide on the inner side of the barrel 7. Below the lower 20 portion 32 of the collar 30, I provide the mandrel with packing collars 33 and between these collars and the collar 30 I provide packing rings 34. These packing rings increase the efficiency of the tool by preventing air from being supplied 25 to the lower end of the mandrel in the valve seat when the valve opens and insuring that the only air that can pass to the valve must pass up through the perforated suction head 22.

By correlating the pins and slots employed 30 for effecting the opening of the valve in such a way that the pins 15 of the valve can operate in the longitudinal slots 20 instead of in the helical slots 21, it is possible to transform this perforation cleaner into a bottom bailer operating on this same general principle of suddenly reduced pressure. Figure 7 illustrates the tool transformed in this way. In Figure 7, 7a indicates the barrel of the tool mounted on a mandrel 6a. In this tool the lower end of the bushing 25a rests on the collar 30a while the tool is running down the well; but in assembling the tool the valve pins, such as the valve pin 15a, are put in place to run in the straight slots or longitudinal slots 20a of the actuator cam 9a. 45 The lower end of the barrel 7a attaches to a coupling 8a, corresponding to the coupling 8 of Figure 2, and a sand barrel 23a is provided below this point carrying an ordinary bailer shoe 35. If desired, a coiled spring 36 may be provided 50 around the mandrel 6a and between the packing collar 33a and the upper end of the actuator sleeve 9a. This spring is a light spring, the function of which is to prevent any accidental or premature upward movement of the barrel 7a which 55 might be sufficient to open the valve when the tool is running down the well.

In addition to inserting the pins 15a in the slots 20a in the assembly shown in Figure 7, the pins 19a of the cam member 13a are inserted in 60 the helical slots 21a. With this arrangement of parts, it will be evident that when the bailer shoe 35 strikes the well bottom an upward movement of the barrel 7a will occur and the actuator sleeve 9a will also move upwardly. When this movement occurs, the helical slots 21a in the actuator sleeve will cause a relative rotation of the valve and cam member 13a, thereby causing the valve pins 15a to ride up on the cam edges 14a to open the valve.

In this tool shown in Figure 7, it will be evident that the entire weight of the tool is not on the well bottom but only the weight of the valve 7a plus the pressure of the light spring 36.

In Figure 9 I illustrate a modified embodiment 75

of the type of tool shown in Figure 7, in which the barrel is guided on the mandrel below the valve as well as above it. The tool, however, operates in substantially the same way as the tool illustrated in Figure 7. In the construction shown in Figure 9, I provide a mandrel 37 with a lower extension 38 which may be connected to the same by a coupling 39 which may carry the flap valve 40 for retaining the charge. The lower portion 10 of the mandrel 37 then operates as a sand barrel. In other words, the flap valve 40 would be at a considerable distance below the valve which is located at about the level of the actuator sleeve 41. The lower end of the extension 38 is formed 15 with packing collars 42 which run in a lower barrel 43. In running down the well, the lower end of the coupling 44 rests on the upper packing collar 42. When the shoe 45 attached to the lower end of the barrel 43 strikes the well bottom, 20 the barrel 43 slides upwardly and this upward movement raises the actuator sleeve 41 and opens the valve. If desired, a cushion spring 46 may be provided between the upper end of the shoe 45 and the lower end of the mandrel extension 38. 25 In the operation of the tool as a perforation cleaner, the jar to dislodge the relatively movable member or barrel 7 may be imparted in any manner but preferably by lowering the tool and suddenly stopping the lowering movement. This 30 gives a snap action or jar to the tool which will dislodge the relatively movable member or barrel 7, thereby operating the valve.

The spring 18 of the valve is preferably attached to the valve so that torsion in the spring 35 tends to keep the valve pins 15 up against the actuating edge of the helical slot 21. This insures that there will be no lost motion in the operation of the tool. In other words, as soon as the relative longitudinal movement of the actuator sleeve 9 40 occurs, the valve will immediately commence to open.

The mode of operation of the tool when used as a perforation cleaner consists in running the tool down the well until the suction head 22 is located opposite the perforations of the screen 2 45 in the well. Then by a sudden down movement and snap action or jar on the sand line, the inclined shoulder 29 on the bushing 25 of the barrel will compress the spring ring 28 and release the barrel 7. The barrel 7 carrying with it the actuator sleeve 9 will then move downwardly. In this movement the pins 19 on the cam member 13 running in the straight slots 20 will prevent rotation of the actuator sleeve. Its helical slots 21 will, therefore, move the pins 15 of the valve to cause a relative rotation of the valve in the cam member, thereby causing the valve pins 15 to ride up on the cam edges 14 to open the valve. By reason of the presence of the low pressure air chamber 10 there will be a sudden reduction in pressure within the casing opposite the perforations 3 and there will be immediately developed an inrush of material through the perforations of the screen to clear it. Material taken in in this way will be drawn into the suction head 22 60 through its perforations and up into the sand barrel 23 above the bottom valve 24, which being of the check valve type permits this material to pass upwardly freely. This valve 24 then closes immediately to retain the charge.

In the reassembly of the parts of the tool illustrated in Figure 7 to transform the perforation cleaner into an ordinary bottom bailer, the mode of operation of the tool is substantially the same except that the spring ring 28 used in the clean-

ing of perforations is removed from the tool and the shoe 35 is substituted for the suction head 22 shown in Figure 1. In the assembly of Figure 7, it should be remembered that the pins 19a of the cam member run in the helical slots 21a instead of the straight slots. When the shoe 35 strikes bottom a relative upward movement of the barrel 7a occurs and the helical slots 21a give a rotation of the cam member 13a in a right hand direction, thereby causing the cam edges 14a to ride forwardly under the valve pins 15a to lift the valve. 10

It is understood that the embodiment of the invention described herein is only one of the many embodiments this invention may take and I do not wish to be limited in the practice of the invention, nor in the claims, to the particular embodiment set forth. 15

What I claim is:

1. A tool of the kind described, having a low pressure air-tight chamber within the same, a valve for maintaining the air-chamber closed while the tool is running down the well, said tool including a relatively fixed part and a relatively movable part capable of vertical movement on the fixed part, yieldable means between the fixed part and the movable part, one of said parts having a shoulder temporarily engaging the yieldable means for temporarily holding the relatively movable part against longitudinal movement on the fixed part and cooperating with the yieldable means when a jar is imparted to the relatively fixed part, to move the yieldable means off the shoulder to release the relatively movable part and thereby cause relative downward movement of the relatively movable part of the fixed part, and means actuated by said relative downward movement for opening the valve.

2. A tool of the kind described, having a casing with a low pressure air-chamber within the same, a valve for maintaining the air-chamber closed while the tool is running down the well, a spring associated with the valve for normally holding the same closed, said casing including a relatively fixed part and a relatively movable part, yieldable means mounted between the relatively fixed part and the relatively movable part for temporarily holding the relatively movable part against longitudinal movement on the fixed part and operating when a jar is imparted to the relatively fixed part, to become dislodged from the relatively fixed part, and thereby release the relatively movable part, and cause a relative downward movement of the same on the fixed part, and means actuated by the relatively movable part during its said relative movement to open the valve.

3. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering recesses therein forming a pocket, yieldable means mounted in said pocket, one of said two parts having a shoulder engaging the yieldable means for temporarily holding the relatively movable part against longitudinal movement on the fixed part and cooperating with the yieldable means upon a sudden relative upward movement of the relatively fixed part, to release the relatively movable part and thereby cause relative downward movement of the relatively movable part on the fixed part, and means actuated by said

relatively movable part in said relative downward movement, for opening the valve.

4. A tool of the kind described, having a low pressure-air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering circumferential recesses therein forming an annular pocket, a spring-ring mounted in said pocket, one of said two parts having a shoulder engaging the spring-ring for temporarily holding the relatively movable part against longitudinal movement on the fixed part and cooperating with the spring-ring when a jar is imparted to the relatively fixed part, to release the relatively movable part and thereby cause relative downward movement of the relatively movable part on the fixed part, a cam, said valve having means actuated by said relatively movable part in said relative downward movement, for opening the valve.

5. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering circumferential recesses therein registering together to form an annular pocket, a spring-ring mounted in said pocket, one of said two parts having an inclined shoulder engaging the spring-ring for temporarily holding the relatively movable part against longitudinal movement on the fixed part and cooperating with the spring-ring when a jar is imparted to the relatively fixed part, to release the relatively movable part and thereby cause relative downward movement of the relatively movable part on the fixed part, and means actuated by said relatively movable part in said relative downward movement, for opening the valve.

6. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering circumferential recesses therein registering together to form an annular pocket, a spring-ring mounted in said pocket, one of said two parts having an inclined shoulder engaging the spring-ring for temporarily holding the relatively movable part against longitudinal movement on the fixed part and cooperating with the spring-ring when a jar is imparted to the relatively fixed part, to release the relatively movable part and thereby cause relative downward movement of the relatively movable part on the fixed part, a cam, means on the valve cooperating with the cam whereby relative rotation of the cam and valve will open the valve, and means actuated by said relatively movable part in said relative downward movement thereof, for effecting a relative rotation of the cam and valve to open the valve.

7. A tool of the kind described, having a low pressure air-tight chamber within the same, a valve for maintaining the air-chamber closed while the tool is running down the well, said tool including a relatively fixed part and a relatively

movable part capable of vertical movement on the fixed part, said two parts having adjacent circumferential walls with registering circumferential recesses therein registering together to form an annular pocket, a spring-ring mounted in said pocket, one of said two parts having an inclined shoulder engaging the spring-ring for temporarily holding the relatively movable part against longitudinal movement on the fixed part and cooperating with the spring-ring when a jar is imparted to the relatively fixed part, to release the relatively movable part and thereby cause relative downward movement of the relatively movable part on the fixed part, a cam, said valve having means cooperating with the cam upon a relative rotary movement of the valve and cam, to open the valve, an actuator sleeve rigid with said relatively movable part and having a substantially helical guideway therein cooperating with said valve and cam when said relatively movable part moves downwardly, to open the valve.

8. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering circumferential recesses therein registering together to form an annular pocket, a spring-ring mounted in said pocket, one of said two parts having an inclined shoulder engaging the spring-ring for temporarily holding the relatively movable part against longitudinal movement on the fixed part and cooperating with the spring-ring when a jar is imparted to the relatively fixed part, to release the relatively movable part and thereby cause relative downward movement of the relatively movable part on the fixed part, an actuator sleeve rigid with said relatively movable part and having a substantially helical slot therein engaging the valve and operating when the said relative downward movement of the relatively movable part occurs, to effect a relative rotation of the valve and cam to open the valve, and means for preventing relative rotation of the relatively movable part on the relatively fixed part when the relatively movable part has its relative downward movement.

9. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering recesses therein forming a pocket, yieldable means mounted in said pocket, one of said two parts having a shoulder engaging the yieldable means for temporarily holding the relatively movable part against longitudinal movement on the fixed part and cooperating with the yieldable means, when a jar is imparted to the relatively fixed part to release the relatively movable part and thereby cause relative downward movement of the relatively movable part on the fixed part, an actuator sleeve rigidly carried by the relatively movable part and having a longitudinal slot therein, means fixed with respect to the relatively fixed part and lying in the slot for preventing rotary movement of the relatively movable part when the same has its said relative downward move-

- ment, said actuator sleeve having a substantially helical slot, said valve having means engaging the said helical slot to effect rotation of the sleeve when the relatively movable part has its said relative downward movement, and a relatively fixed cam cooperating with the said means on the valve to open the valve when the valve is rotated
10. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering recesses therein forming a pocket, movable yieldable means mounted in said pocket, one of said two parts having a shoulder engaging the yieldable means for temporarily holding the relatively movable part against longitudinal movement on the fixed part and cooperating with the yieldable means when a jar is imparted to the relatively fixed part, to release the relatively movable part and thereby cause relative downward movement of the relatively movable part on the relatively fixed part, an actuator sleeve carried by the relatively movable part and having a longitudinal slot therein, a projection on the relatively fixed part received in the said slot for preventing rotation of the relatively movable part when it has its relative downward movement, said actuator sleeve having a substantially helical slot therein and said valve having a projection received in said helical slot, and a relatively fixed cam cooperating with the projection on the valve and the helical slot to open the valve when the relatively movable part has its said relative downward movement.
40. 11. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering recesses therein forming a pocket, movable yieldable means mounted in said pocket, one of said two parts having a shoulder engaging the yieldable means for temporarily holding the relatively movable part against longitudinal movement on the fixed part and cooperating with the yieldable means when a jar is imparted to the relatively fixed part, to release the relatively movable part and thereby cause relative downward movement of the relatively movable part on the relatively fixed part, an actuator sleeve carried by the relatively movable part and having a longitudinal slot therein, a projection on the relatively fixed part received in the said slot for preventing rotation of the relatively movable part when it has its relative downward movement, said actuator sleeve having a substantially helical slot therein and said valve having a projection received in said helical slot, a cam fixed on the relatively fixed part cooperating with the projection on the valve and the helical slot to open the valve when the relatively movable part has its said relative downward movement, said relatively fixed part having means at its lower end for securing a bailer shoe to the same, a projection on the valve being capable of running in the longitudinal slot, and the projection on the relatively fixed member being capable of running in the helical slot,

thereby enabling a relative upward movement of the relatively movable part to effect a relative rotation of the valve and cam to open the valve.

12. A tool of the kind described, having a low pressure air-tight chamber within the same, a valve for maintaining the air-chamber closed while the tool is running down the well, said tool including a relatively fixed part and a relatively movable part capable of vertical movement on the fixed part, said two parts having adjacent circumferential walls with registering recesses therein forming a pocket, movable yieldable means mounted in said pocket, one of said two parts having a shoulder engaging the yieldable means for temporarily holding the relatively movable part against longitudinal movement on the fixed part, an actuator sleeve carried by the relatively movable part having a longitudinal slot therein, a pin on the relatively fixed part running in the said slot, said actuator sleeve having a substantially helical slot, a pin on the valve running in the said helical slot, a cam fixed with respect to the relatively fixed part and cooperating with the said valve's pin to open the valve, said actuator sleeve being capable of attachment in a second position with the first-named pin received in the helical slot and with the said valve's pin received in the longitudinal slot, thereby enabling a relative upward movement of the relatively movable part to effect relative rotation of the valve and cam to open the valve.

13. A tool of the kind described, having a low pressure air-tight chamber within the same, a valve for maintaining the air chamber closed while the tool is running down the well, said tool including a relatively fixed part and a relatively movable part capable of vertical movement on the fixed part, an actuator sleeve rigid with the relatively movable part having a substantially helical slot therein, a pin on the relatively fixed part running in the said helical slot, said actuator sleeve also having a longitudinal slot, a pin on the valve running in the said longitudinal slot, and a cam fixed with respect to the relatively fixed part cooperating with the valve pin to open the valve upon a relative upward movement of the relatively movable member, the first-named pin being capable of running in the longitudinal slot, and the valve pin being capable of running in the substantially helical slot thereby enabling the actuator sleeve to be attached in a second position in which the relatively movable part can open the valve by a relative downward movement instead of an upward movement.

14. A tool of the kind described, having a tubular mandrel with an air-tight chamber therein, a barrel enveloping the mandrel and capable of downward movement thereon, the outer surface of said mandrel having a circumferential groove therein, the inner surface of said barrel having a circumferential groove therein capable of registering with the first-named circumferential groove to form an annular pocket, a spring-ring mounted in said pocket and normally preventing relative movement of the barrel on the mandrel, a valve for maintaining the air-chamber closed while the tool is running down the well, an actuator sleeve rigid with the barrel, a spring associated with the valve, and cam means associated with the valve, said actuator sleeve having means cooperating with the valve and the cam to open the valve when a relative downward movement of the barrel occurs with respect to the mandrel, said spring-ring operat-

ing when a jar is imparted to the mandrel to release the barrel for relative downward movement and thereby effect the opening of the valve.

15. A tool of the kind described, having a low pressure air-tight chamber within the same, a valve for maintaining the air chamber closed while the tool is running down the well, said tool including a tubular mandrel, a barrel enveloping the mandrel, normally in a depressed position and capable of vertical upward movement on the mandrel, a shoe carried by the barrel, an actuator sleeve carried by the barrel to move relatively upwardly on the mandrel when the shoe strikes an obstruction or the well bottom, 15 stop-means for limiting the upward movement of the barrel on the mandrel, cam-means cooperating with the valve, said actuator sleeve having means for effecting a relative rotation of the valve and cam-means, to open the valve before the barrel engages the stop-means, whereby the entire weight of the tool does not come upon the shoe.

16. A tool of the kind described, having a low pressure air-tight chamber within the same, a 25 valve for maintaining the air chamber closed while the tool is running down the well, said tool including a tubular mandrel, a barrel enveloping the mandrel, normally in a depressed position and capable of vertical upward movement 30 on the mandrel, a shoe carried by the barrel, an actuator sleeve carried by the barrel to move relatively upwardly on the mandrel when the shoe strikes an obstruction or the well bottom, stop-means for limiting the upward movement 35 of the barrel on the mandrel, cam-means cooperating with the valve, said actuator sleeve having means for effecting a relative rotation of the valve and cam-means, to open the valve before the barrel engages the stop-means, whereby the 40 entire weight of the tool does not come upon the shoe, and a spring between the mandrel and the barrel to press the shoe against the well bottom when the shoe strikes the same.

17. A well tool of the kind described, having a 45 low pressure air-tight chamber within the same, a valve for maintaining the air chamber closed while the tool is running down the well, said tool including a relatively fixed part and a relatively movable part capable of vertical shifting movement on the fixed part, means including a shoulder and a yieldable member temporarily engaging the shoulder for normally preventing movement of the relatively movable part on the relatively fixed part while the tool is running down 50 the well, said yieldable member enabling a jar to the tool to dislodge the yieldable member from the shoulder and cause a shifting of the relatively movable part on the relatively fixed part for effecting the opening of the said valve.

18. A well tool of the kind described, having a low pressure air-tight chamber within the same, a valve for maintaining the air chamber closed while the tool is running down the well, said tool including a relatively fixed part and a relatively 65 movable part capable of vertical shifting movement on the fixed part, means including a shoulder and a yieldable member engaging the shoulder for normally preventing movement of the relatively movable part on the relatively fixed part while the tool is running down the well, said 70 yieldable member enabling a jar to the tool to dislodge it from said shoulder and cause a shifting of the relatively movable part on the relative-

ly fixed part, and valve opening means brought into action by the relative movement of the relatively movable part on the relatively fixed part for opening the valve, said yieldable member constructed so that it will operate to permit the relatively movable member to maintain itself in its shifted position after the shifting movement has occurred.

19. A well tool of the kind described, having a low pressure air-tight chamber within the same, 10 a valve for maintaining the air chamber closed while the tool is running down the well, said tool including a relatively fixed part and a relatively movable part capable of vertical shifting movement on the fixed part, means including a 15 shoulder and a yieldable member engaging the shoulder for normally preventing movement of the relatively movable part on the relatively fixed part while the tool is running down the well, said yieldable member enabling a jar to the tool 20 to cause a shifting of the relatively movable part on the relatively fixed part, and means for effecting the opening of the valve brought into action by jarring the yieldable means off the shoulder.

20. A well tool of the kind described, having 25 a low pressure air-tight chamber within the same, a valve for maintaining the air chamber closed while the tool is running down the well, said tool including a relatively fixed part and a relatively 30 movable part capable of vertical shifting movement on the fixed part, means including a shoulder and a yieldable member engaging the shoulder for normally preventing movement of the relatively movable part on the relatively fixed part while the tool is running down the well, said yieldable member enabling a jar to the tool 35 to cause a shifting of the relatively movable part on the relatively fixed part, valve opening means, said valve opening means and said valve being relatively rotatable with respect to each other, and actuating means carried by the relatively movable part for effecting a relative rotation between the valve opening means and the valve when the relatively movable part is moved 40 on the relatively fixed part, to effect the opening 45 of the valve.

21. A well tool of the kind described, having a low pressure air-tight chamber within the same, a valve for maintaining the air chamber closed 50 while the tool is running down the well, said tool including a relatively fixed part and a relatively movable part capable of vertical shifting movement on the fixed part, means including a shoulder and a yieldable member engaging the shoulder for normally preventing movement of the relatively movable part on the relatively fixed part while the tool is running down the well, said yieldable member enabling a jar to the tool to cause a shifting of the relatively movable 55 part on the relatively fixed part, valve opening means having a cam edge, said valve opening means and said valve being relatively rotatable with respect to each other, and said valve having a pin engaging the cam edge, and actuating means carried by the relatively movable part having slots therein for engaging the said pin and the said valve opening means for effecting a relative rotation of the valve and the valve opening means when a relative movement of the relatively movable member on the relatively fixed member occurs, to open the valve.

WILLIAM J. FLURY.
